UNITED STATES PATENT OFFICE

ARTHUR F. POOLE, OF WESTPORT, CONNECTICUT, ASSIGNOR TO THE WAHL COMPANY,
OF CHICAGO, ILLINOIS, A CORPORATION OF DELAWARE

LEAD PENCIL

Application filed October 15, 1924. Serial No. 743,841.

My invention relates to new and useful improvements in lead pencils and more particularly to a mechanical pencil of that type employing a plunger for propelling a lead and 5 provided with a magazine for holding extra leads.

Among the objects of my invention are to provide a construction wherein the pencil casing is composed of sections which may be 10 readily separated for the introduction of leads to the lead magazine or for placing a single lead in position to be propelled through the pencil tip; to provide a simple and efficient construction for propelling the lead to 15 the pencil tip as well as means for guiding the lead through the casing; to provide a novel pencil construction wherein the lead magazine is arranged in the casing between the lead propelling mechanism and the tip, 20 together with a two part separable casing so arranged that the tip portion of the pencil may be detached from the remainder of the casing in such a manner that the lead magazine is exposed and so that a new lead may 25 be readily and quickly transferred from the magazine into lead propelling position; to provide a novel pencil construction wherein the lead magazine is arranged contiguous to the pencil tip, together with a two part casing 30 adapted to separate between the tip portion and the magazine portion so as to permit the quick transfer of the lead from the magazine to the tip, such construction including a lead guide constructed and arranged to assist 35 in the guidance of the lead during the transferring operation; to provide a novel pencil construction including a rubber erasing member disposed at the rear end of the pencil and a cooperative lead propelling member which 40 is constructed and arranged to force the rubber eraser outwardly as it becomes worn; to provide an improved construction for attaching the clip to the pencil casing; to provide 45 these and other objects of invention which will be more apparent from a perusal of the following specification when taken in connection with the accompanying drawings wherein:

Figure 1 is a longitudinal section through 50 the pencil.

Figure 2 is a fragmental longitudinal section on a plane at right angles to that shown in Figure 1.

Figure 3 is a longitudinal section through a slightly modified form of pencil.

Figure 4 is a fragmental longitudinal section on a plane at right angles to that shown in Fig. 3.

Figure 5 is a section on line 5—5 of Figure 1.

In carrying out my invention I provide a casing formed of the cylindrical section 1 and the conical section 2 which are connected by the sleeve 3, that end of the sleeve extending within the end of the section 1 being soldered or secured thereto in any other suitable manner and that section extending into the section 2 being exteriorly threaded to engage interior threads formed in the large end of the section 2. That end of the sleeve which is in 70 the section 1 is interiorly beveled, as shown at 4, for a purpose which will appear as the description proceeds, and the outer or small end of the section 2 is interiorly threaded to receive the threaded shank 5 of a tip 6 which 75 is provided with ridges as shown in the patent to Keeran No. 1,151,016. The end of the section 2, connected to the sleeve 3, is provided with a bead 7 which aids in concealing the joint between the two sections. A guide tube 80 is secured in the conical section 2 by means of a washer 9 which is secured to both the tube and interior of the section, and as shown, the inner end of the tube is exteriorly beveled and secured to the interior of the section at 85 10. The parts are preferably secured by soldering or may be secured in any other suitable manner. The inner end of the guide tube extends within the sleeve 3 and is interiorly beveled as shown at 11 to form a guide 90 for the insertion of a lead as well as to position the propelling plunger rod, to be later described.

Secured within the opposite end of the section 1 is a sleeve 12 having the arm 13 of a 95 spring clip 14 secured thereto by soldering or other means, said arm of the spring clip being received in a slot formed in the section of the casing. Adjacent the outer end the sleeve 12 has a collar 15 spun therein adapted 100

to be received in a groove formed around the exterior of a cap 16, such connection allowing the cap to be rotated with respect to the sleeve. A washer 17 is received in the cap and forms an abutment for the inner end of an eraser 18 which is held in the cap by the in-turned edge 19 which embeds itself in the eraser.

The cap 16 has a longitudinal bore which receives the end of a tube 20 having interior screw threads 21 rolled therein, said tube being connected to turn with the cap. Secured within the section 1, of the casing, intermediate the ends and spaced from the inner end of the threaded tube 20, is a collar 22 forming a support for the inner ends of the sections 23 and 24 of a plunger tube. The section 23 of the plunger tube extends through the threaded tube 20 and has a slot 25 formed therein to receive the offset portion 26 of a plunger rod 27, the offset portion having notches 28 therein to receive the threads 21 of tube 20. The outer end of the section 24, of the plunger tube, is received in the beveled end 11 of the guide tube 8 and the plunger rod 27 is adapted to extend through the sections 23 and 24 of the plunger tube and enter the guide tube 8 to propel a lead through the guide tube and tip 6. An extension 29 is formed on the offset portion 26, of the plunger rod, and operates in the plunger tube. This extension is adapted to engage the washer 17 and force the eraser from the cap 16. It will be understood that it will be desirable to force the eraser from the cap as it becomes worn so that the eraser may be used substantially its entire length. The pencil lead in position to be propelled is shown as 30 and the extra leads are shown at 31.

Having fully described the detailed construction, it is thought that the manner of using as well as the advantages will be clearly understood. With the parts assembled as shown in the drawings the lead 30 within the guide tube 8 is adapted to be propelled by means of the plunger rod 27. The lead will be propelled through the tip 6 and will be held within said tip against rotary movement, in the manner shown in the patent to Keeran above referred to. When it is desired to propel the lead, the cap 16 will be rotated and in turn will rotate the threaded tube 20. The notches 28, in the offset portion 26, of the plunger rod 27, engage the threads in the tube 20, as previously described, and therefore, when the threaded tube is rotated the plunger rod 27 will be slid longitudinally within the sections 23 and 24 of the plunger tube. The said plunger rod enters the guide tube 8, engages the inner end of the lead 30, and therefore propels the lead when operated. By reversing the operation the extension 29, on the offset portion 26, of the plunger rod 27, will engage the washer 17, in the cap, and force the eraser 18 from the cap. The extra leads 31 are received in the section

1 of the casing and their movement therein will be limited by the collar 22. The extra leads will surround the section 24 of the plunger tube and space is provided preferably for twelve extra leads, although, of course, it will be understood that by increasing or decreasing the space any number of extra leads might be held. When it is desired to insert a new lead in the guide tube 8, the conical section 2, of the casing, is disengaged from the threaded end of the sleeve 3. By inclining the cylindrical section 1, the extra leads 31 will pass through the sleeve 3 and one lead may be removed and placed into the guide tube 8. The beveled end 4 of the sleeve 3 acts to guide the extra leads through said sleeve. After the extra lead has been placed in the guide tube 8 the conical section 2 will again be engaged with the sleeve 3. Of course, it will be understood that in order to insert a new lead the cap 16 must be rotated in reverse direction to the propelling movement so as to draw the plunger rod 27 from the end of the guide tube 8. By beveling the end of the guide tube 8 as shown at 11 the lead will be guided into the tube.

In Figures 3 and 4 I have illustrated a slightly modified form of invention in which the casing is made up of the cylindrical section 32 and conical section 33 connected by a sleeve 34. That end of the sleeve 34 extending into the conical section 33 is soldered to that section, whereas that end which enters the cylindrical section 32 is exteriorly threaded to engage interior threads in the section. The sleeve 34 is interiorly beveled from the threaded end as shown at 35 for a purpose which will later appear. A guide tube 36 is carried in the conical section 33 and has one end received in the sleeve 34, said end being interiorly beveled as shown at 37 and forming a continuation of the bevel 35 of the sleeve. The opposite end of the guide tube 36 is exteriorly beveled and connected to the interior of the section 33 at 38, the end of the section 33 being interiorly threaded to receive the threaded shank 39 of the tip 40. The tip will be provided with ridges such as described in the preferred form of the invention and shown in the patent to Keeran previously referred to. A bead 41 is formed on the end of the conical section 33 and aids to hide the joint at the point where the two sections are connected.

Secured within the opposite end of the section 32 is a sleeve 42 to which is soldered, or otherwise secured, the arm 43 of a spring clip 44. The arm 43 is received in a slot formed in the section 32. The section 32 has a collar 45 spun adjacent its outer end and the collar is adapted to be received in a groove 46 formed in the exterior of a cap 47. The cap has a recess formed in its outer end to receive an eraser 49 and the inner end is provided with a projection 50 to which is se-

cured, by soldering or other means, the end of a tube 51 having interior screw threads 52 rolled therein. A collar 53 is secured in the section 32 intermediate the ends thereof and forms a support for the inner ends of sections 54 and 55 of a plunger tube. The section 54 has a slot 56 extending substantially throughout its length and this slot forms a guide for the offset portion 57 of the plunger rod 58. This offset portion is provided with diagonally extending notches 59 adapted to engage the threads 52 of the tube 51 so that as the tube 51 is rotated by the cap 47, the plunger rod will be fed longitudinally, through the sections 54 and 55 of the plunger tube.

The outer end of the section 55 of the plunger tube is received in the conical recess 35 of the sleeve 34 and terminates a short distance from the beveled end of the guide tube 36. As shown, the plunger rod 58 is adapted to enter the guide tube 36 to propel the lead 60 through the guide tube and tip 40. The extra leads 61 are held in the section 32, of the casing, around the section 55 of the plunger tube, and their inner movement is limited by the collar 53.

The operation in the modified form of the invention is substantially the same as that described for the preferred form. With the parts assembled in the position shown the lead 60 may be propelled through the guide tube 36 and tip 40 by the rotation of the cap 47 which in turn rotates the threaded tube 51 which feeds the plunger rod 58 longitudinally through the plunger tube. When it is desired to insert a new lead the direction of feed of the plunger rod is reversed by turning the cap 47 in the opposite direction and this removes the end of the plunger rod from the guide tube 36. The section 33 of the casing is then disconnected from the cylindrical section 32, by rotating to disengage the threads. By slightly tilting the cylindrical section 32 one of the extra leads may be removed and placed into the guide tube 36. The lead will be properly directed into the guide tube by the beveled portion 35 of the sleeve 34 and the beveled end 37 of the guide tube. After the new lead is inserted the sections 32 and 33 are again connected and the new lead may be fed through the tube and tip by the operation of the plunger.

By the construction shown in both forms of the invention clogging of the guide tube is prevented for the reason that the end of the plunger tube is in close proximity to the end of the guide tube, and lead which may become broken in connecting the two sections of the casing, cannot fall into the guide tube or clog the same.

It will be noted that by providing a pencil construction wherein the casing is separable at a point intermediate the rear end of the

pencil tip or lead guide 8, and the front end of the lead magazine, and especially in arranging the lead guide with a tapered forward portion, the facile transfer of the lead from the magazine to the lead guide in the pencil tip is secured.

Having fully described my invention, what I claim and desire to secure by Letters Patent is:—

1. A pencil comprising a casing section having a central lead guide tube, lead propelling mechanism including a threaded tube and a plunger adapted to be moved through said lead guide, a pencil tip detachably connected to the front of said casing section and having a lead guide tube adapted to register with the lead guide tube of said casing section, the rearmost portion of said lead guide tube of said pencil tip having a beveled mouth to facilitate the entry of said lead into said tip lead guide tube, said casing section having a lead magazine disposed about said casing lead guide tube and having an open end positioned adjacent and opposite the beveled mouth of said tip lead guide tube to facilitate the transfer of lead from said magazine to the lead guide tube of said tip.

2. A pencil comprising a casing section having a central tubular lead guide terminating substantially at the front end of said casing, lead propelling mechanism including a plunger adapted to be moved through said lead guide tube, a pencil tip detachably connectible to the front of said casing section, said tip including a central tube forming a lead guide, said tube having a beveled portion at its rear end to be positioned opposite the front end of the lead guide tube of said casing section when said tip is in position on said casing section, and said casing section having a lead magazine disposed about said tubular lead guide.

3. In a pencil, a casing section having a central lead guide in its front portion and a slotted plunger tube in its rear portion, a tip at the front end of said casing and an eraser seat at the rear end of said casing for holding an eraser, a plunger operable in said lead guide, means for moving said plunger toward said tip and toward said eraser seat, and means to cause said plunger to push said eraser outwardly upon a predetermined movement of said plunger.

4. In a pencil provided with a slotted plunger tube in its front portion, the combination of a casing, a tip at the front end of said casing, an eraser seat at the rear end of said casing for retaining an eraser, a lead propelling mechanism operable in said plunger tube for advancing a lead through said tip, and means operable by the movement of said lead propelling mechanism for pushing said eraser outwardly in its seat to compensate for the wear on the eraser.

5. A mechanical pencil comprising a cas-

- ing having a tip secured to one end thereof and adapted to receive a lead, a partition in the casing intermediate its ends, for forming two compartments, the compartment adjacent 5 to the tip adapted for receiving extra leads, a plunger tube carried by the partition and extending longitudinally of the casing, that end of the tube entering the compartment removed from the tip having an elongated 10 opening therein, a plunger slideable in the plunger tube and having an offset portion received in the elongated opening, an interiorly threaded tube rotatably mounted on the end of the plunger tube having the opening therein 15 and adapted for engaging the offset portion on the plunger, and means for rotating the threaded tube for operating the plunger to propel the lead in the tip.
6. In a pencil, the combination of a casing 20 provided with a centrally disposed tubular lead guide and provided at its front end with an interiorly disposed thread, a pencil tip having a portion provided with an external thread adapted to engage the interior threads 25 on the front end of said casing whereby to permit the detachable connection of said pencil tip to said casing, said pencil tip having a centrally disposed lead guide tube adapted to be positioned directly opposite 30 the mouth of said tubular lead guide of said casing when said tip is positioned on said casing, a lead magazine disposed about said tubular lead guide, said lead guide tube on said tip having a flaring mouth to assist the 35 feed of said lead into said pencil tip lead guide tube, and means for propelling a lead through said lead guide tube.
7. A pencil comprising a casing, a point 40 portion secured to one end thereof, an eraser holder for retaining an eraser seated therein at the other end of said casing, a plunger guide tube provided with a slot, a plunger rod carrying a member adapted to project through said slot and having grooves, and 45 threaded actuating means arranged around said guide tube and engaging said grooves, said plunger rod being provided with extending portions on each end of said projecting member for expelling said eraser or a lead in said point portion.
8. A pencil comprising a casing, a plunger 50 guide tube provided with a slot, a plunger rod carrying at an intermediate point thereof a member adapted to project through said slot, helical actuating means arranged around said guide tube and adapted to cooperate with said projecting means to effect longitudinal movement of the plunger, means on the exterior of the pencil to operate said helical actuating means, means for retaining a lead at one end and means for retaining an eraser at the other end of the pencil so that either may be expelled by the plunger rod.
9. A pencil comprising a casing, a point 65 portion secured to one end thereof, an eraser holder for retaining an eraser seated therein at the other end of said casing, a slotted guide tube located centrally thereof, a plunger rod having an intermediate portion bent outwardly so as to project through the slot, the ends 70 of said rod being aligned and located in said tube, and a threaded cylinder within said casing surrounding said slotted guide tube and adapted to be rotated from the outside of said casing, said projecting portion of the 75 plunger rod being provided with means adapted to cooperate with said threaded cylinder to cause the plunger rod to be moved in either direction for expelling said eraser or a lead carried in said tube and point portion.
10. A pencil comprising a substantially uniform hollow stem portion, a tapered point portion removably attached thereto, a central elongated tube secured in said point portion and being provided with a bevelled end, a transverse partition in said stem portion dividing said stem into a front magazine chamber and a rear chamber, a guide member passing through said partition, and adapted to 80 be received in said bevelled end of said tube, the rear section of said guide member being slotted, a plunger in said guide member having a projection extending through said slot, and actuating means in said rear chamber operable from the outside of the pencil and adapted to cooperate with said projection to move the plunger longitudinally, said magazine chamber being empty except for the 85 guide member.
11. A pencil comprising a substantially uniform hollow stem portion, a tapered point portion removably attached thereto, a lead point guide tube carried in said point portion, said tube being of substantial length 90 for the convenient changing of lead thereinto and having its rear end beveled for easy insertion of said lead, a transverse partition in said stem portion dividing said stem into a front magazine chamber and a rear chamber, a guide member passing through said partition and supported thereby, said member being slotted in the rear chamber and extending into proximity to the lead point guide in the magazine chamber, a plunger in said 95 guide member having a projection extending through said slot, and actuating means in said rear chamber operable from the outside of the pencil and adapted to cooperate with said projection to move the plunger longitudinally, said magazine chamber being thus rendered available by removing said point portion, whereupon the beveled end of the lead point guide tube is located in close proximity to the open end of said magazine chamber.
- In witness whereof, I hereunto subscribe my name to this specification.
